UNITED STATES PATENT OFFICE.

THOMAS F. HATHAWAY, OF ELGIN, ILLINOIS, ASSIGNOR TO ELGIN AMERICAN MANUFACTURING CO., OF ELGIN, ILLINOIS, A CORPORATION OF ILLINOIS.

CIGARETTE-CASE.

1,156,598.

Specification of Letters Patent.

Patented Oct. 12, 1915.

Application filed December 19, 1914. Serial No. 878,114.

To all whom it may concern:

Be it known that I, THOMAS F. HATHAWAY, a citizen of the United States, residing at Elgin, in the county of Kane and State 5 of Illinois, have invented certain new and useful Improvements in Cigarette-Cases, of which the following is a specification.

The present invention relates to a case or receptacle particularly designed and adapted 10 for containing cigarettes, cigars, matches and the like.

The objects of the invention are to provide a case in which the articles carried therein can be extracted therefrom without requiring 15 the user to open the lid and reach inside for that purpose. The extraction being accomplished by simply pulling the foremost article out from the forward end of the case.

A further object of the invention is to 20 form a case of the character described which shall be composed of two sections hinged together, each section being alike and capable of being made from a single die.

A further object of the invention is to 25 give an extended abutting surface for the sections of the case along the sides thereof, giving a substantial bearing for the sections against one another along the sides, whereby the forward end, from which the articles 30 are extracted, may be configured to provide for the easy extraction of the article, no engagement between the sections along the forward end being necessary beyond the engagement along the sides.

A further object of the invention lies in 35 forming the case of a symmetrical and neat appearance due to making the same of two sections, each of the same configuration and counterparts of each other.

The invention further consists in the features of construction and combinations of 40 parts hereinafter described and claimed.

In the drawings: Figure 1 is a top view of the case of the present invention; Fig. 2 is 45 a section on line 2—2 of Fig. 1, looking in the direction of the arrow, and showing the case in closed position in full lines and by means of dotted lines the position assumed by the sections of the case when an article 50 is being extracted; and Fig. 3 is a section on line 3—3 of Fig. 1 looking in the direction of the arrow.

As previously stated, the invention resides in a case or container of the proper size and

width for receiving and carrying cigarettes, 55 cigars, matches and the like, and such container is formed so that an article may be extracted therefrom without the user opening the lid and reaching inside of the same. A suitable opening being provided at the 60 forward end of the case, enabling the user to grasp the foremost of the articles within the case and pull it out through the forward end thereof.

Referring now to the drawings, the case 65 is composed of two sections, 4 and 5, each of which is of similar configuration and is capable of being formed from the same die. This is of material advantage from a manufacturing standpoint, since it reduces 70 the number of tools, reduces the cost of producing the parts, and expedites the assembling of the same. Each section contains a prolonged polished or ornamental surface 75 6, one section forming the top of the case, and the other section forming the bottom, when assembled, although, of course, as to which is the top and which is the bottom would depend upon the position of the case, since each is exactly alike, these sections 80 acting in conjunction do, however, form the component portions of the case.

Each of the sections is rounded at its edges, as at 7, and abut against one another at the point 8 and each section has a relatively elongated slope or curve 9 at its forward end, as will be clearly understood from Fig. 2. Thus the case in cross section partakes of the characteristics of an ellipsoid and is, therefore, easily carried in the 85 pocket and contains no sharp or protruding surfaces which would render it unsightly. The ellipsoid formation gives to it symmetrical appearance, and moreover, forming the case in the manner described gives a 90 bearing surface for each section against the other along the abutting edges of the sides, thus making the case strong and substantial and insuring the sections being maintained in correct alinement. The sections 100 are secured at their rear ends by some suitable form of spring hinge 10.

The articles 11 are arranged within the case transversely thereof as will be understood from Figs. 1 and 2. At the forward 105 end each section is cut away to provide an opening 12 in each section. This opening extends rearwardly of the case a sufficient

depth, so that the central portion of the foremost of the articles within the case is exposed, as will be apparent from Fig. 1. The forward ends of each section are, in the 5 construction shown, bowed or spaced away from one another to provide an opening 13, and the sections are only in engagement at their forward ends at the point 14; that is at the extreme edges of the case. This will 10 be clearly seen from Fig. 3. By so arranging the forward end of the sections withdrawal of the articles therefrom is considerably facilitated, since said forward ends being already curved or spaced apart to some 15 extent by the provision of the opening 13, the amount of expansion of the sections necessary at this point to withdraw the articles is not as great as though the forward ends were in engagement throughout their 20 length. The forward ends 9, as heretofore stated, are formed with a substantially long curve so that the decrease of width in the case toward the forward end is gradual. This is important, since if an abrupt reduc- 25 tion were provided, it would necessarily produce a sharp curve or abutment which would interfere with the free extraction of the article. This is especially important where the case is made for the purpose of 30 carrying cigarettes, since the paper composing the wrapper of the cigarette is easily torn, and if any abutments or projections are encountered in getting the cigarette from the case, the paper would be liable to 35 become torn and the cigarette consequently damaged.

It is thought that the method of using the case is obvious, the user grasping the foremost articles along the surface exposed 40 through the opening 12, and then by pulling upon the article it is pulled out between the forward ends of the sections comprising the case and the extraction operation completed. It will be apparent that this is a much sim- 45 pler operation than it would be if it were necessary to throw the lid open a distance

and the user insert his fingers inside and thus extract the articles required.

To summarize, the case of the present invention permits of the extraction of the article in a simple and easy manner, is so formed that mutilation of the article during extraction is eliminated, is so formed that its forward end from which the article is extracted presents no abrupt surfaces 50 which would be likely to tear the article in extraction, the sections of the case are so formed that a substantial bearing for the sections against one another is afforded along the entire sides thereof, the case is 55 formed of two similar sections, expediting the manufacture and reducing the cost thereof, and by so forming it a symmetrical and smooth contour is given to the case, improving the appearance and rendering it of 60 a nature so that it can be carried in the pocket of the user without producing any 65 objectionable bulging.

I claim:

In a device of the class described, the combination of a case formed of two companion sections connected together by a spring hinge, each section curving at the edges thereof, with the rear and side edges adapted to engage when the device is closed, each 70 section being cut away to provide an opening extending from the forward end thereof toward the rear thereof, and provided with a second cut-away portion at their forward ends to provide a tapered opening extending 75 at right angles to the first mentioned openings and from the forward edges of the first mentioned openings to adjacent the sides of the section, whereby said sections are in engagement only at the sides thereof 80 referring to their forward ends, substantially as described.

THOMAS F. HATHAWAY.
